DISPLAY PANEL FOR MASONRY PRODUCTS

William J. Olson, 65 Cretin Ave., St. Paul, Minn.

Filed Oct. 29, 1964, Ser. No. 82,374

Term of patent 14 years

(Cl. D80—9)

FIG. 1

FIG. 2

FIG. 3

FIG. 1 is a perspective view taken from top, one end and one side of a display panel for masonry products showing my new design;

FIG. 2 is a perspective view taken from the bottom, and side and end opposite that shown in FIG. 1; and

FIG. 3 is an enlarged cross sectional view taken on line 3—3 on FIG. 1.

I claim:

The ornamental design for a display panel for masonry products, substantially as shown.
